United States Patent Office

Des. 181,656
Patented Dec. 10, 1957

181,656

FRYING PAN

Ivar Jepson and Robert O. Ernest, Oak Park, Ill., assignors
to Sunbeam Corporation, Chicago, Ill., a corporation of
Illinois

Application June 7, 1954, Serial No. 30,838

Term of patent 14 years

(Cl. D81—10)

Fig. 1 is a side elevational view of a frying pan embodying my new design;

Fig. 2 is a top plan view of the frying pan;

Fig. 3 is a side elevational view thereof taken from the right of Fig. 1; and

Fig. 4 is an enlarged exploded perspective view of the frying pan embodying the new design of the present invention.

We claim:

The ornamental design for a frying pan, substantially as shown.
